UNITED STATES PATENT OFFICE.

EDWARD WILLIAM MACKENZIE HUGHES, OF CHICAGO, ILLINOIS, ASSIGNOR
TO THE FOX SOLID PRESSED STEEL COMPANY, OF SAME PLACE.

BRAKE-BEAM.

SPECIFICATION forming part of Letters Patent No. 408,021, dated July 30, 1889.

Application filed December 26, 1888. Serial No. 294,684. (No model.)

To all whom it may concern:

Be it known that I, EDWARD WILLIAM MACKENZIE HUGHES, a citizen of Great Britain, residing at Chicago, Cook county, Illinois, have invented a new and useful Improvement 5 in Brake-Beams for Cars or Vehicles, of which the following is a full, true, and exact description, reference being had to the accompanying drawings.

10 The especial objects sought to be obtained in the structure of brake-beams are rigidity, resistance to the strain when the brake is in operation, and lightness and durability of structure. The material most in favor for 15 the structure of these brake-beams is oak; but this, from its nature, is not rigid, and a very trifling spring in the beam results in a great diminution in effective brake-pressure. Oak is likewise very heavy and liable to 20 decay under the conditions of actual use. I have discovered that a beam of peculiar structure made of pressed steel combines to a marked degree the advantages of great rigidity, durability, and lightness.

25 My invention will be readily understood from the accompanying drawings, in connection with this specification.

In my drawings, Figure 1 represents a plan view of my brake-beam with the shoe attached; Fig. 2, an elevation of the same; Fig. 3, a vertical section through Fig. 1 on the line $x x$; Fig. 4, an end view, partly in section, of my brake-shoe and brake-beam, and Fig. 5 a perspective of my brake-beam.

30 My beam itself is made by cutting a piece of steel to the proper configuration and then pressing it between dies upon a suitable machine—say a machine like that for which application for Letters Patent of the United 35 States has been made by Samson Fox, on the 18th day of January, 1888, Serial No. 261,166, now Patent No. 397,178, dated February 5, 1889. In this beam, as shown in Fig. 5, the greatest 40 possible rigidity and lightness are combined. The said beam consists of a box open on its 45 flat side and closed on all other sides, though of course the end parts G might be omitted. This beam increases in width from the end G to the center F. I prefer to make my attachment to this beam by a strap, as shown.

50 In my drawings, A represents the beam.

Surrounding the center of this is the metallic strap B, which can be opened under heat and closed around the beam. It may be fastened in position, if desired, by a bolt H, though I prefer to avoid this as a usual thing, the friction being sufficient to hold the strap in position. This strap completely incloses the beam, as shown, and can then be attached by bolts K to the draft-bars C C. Of course instead of using the draft-bars, as shown, pressure could be applied to the back of the beam, and, if desired, the beam itself could be reversed, so as to place the brake-shoes on the opposite side. The brake-shoe E is carried 60 upon the brake-head D, which has jaws embracing the end of the brake-beam, to which it may be attached by a bolt L, the shoe E being attached to the brake-head by bolts M, if desired. By making this brake-beam of 65 pressed steel I obtain uniformity of structure 70 without liability to fracture.

What I claim as my invention, and desire to secure by Letters Patent, is—

1. A hollow box brake-beam pressed from a 75 flat plate of steel directly into the form of a box having sides, ends, and back, substantially as described.

2. A hollow box brake-beam pressed from a flat plate of steel directly into the form of a 80 box having sides, ends, and back, and having the closed sides of the box curved from G to F, as shown, substantially as described.

3. A hollow box brake-beam pressed from a flat plate of steel directly into the form of a 85 box having sides, ends, and back, and a strap surrounding the same and in contact with the back of the box, substantially as described.

4. A hollow box brake-beam pressed from a flat plate of steel directly into the form of a 90 box having sides, ends, and back, and a strap surrounding the same and in contact with the back of the box, and the brake-heads D and brake-shoes E, substantially as described.

In testimony whereof I have signed my 95 name to this specification in the presence of two subscribing witnesses.

EDWARD WILLIAM MACKENZIE HUGHES.
